(57) **CLAIM**

I claim the ornamental design for an all in one adjustable receiver hitch, as shown and described.

DESCRIPTION

FIG. 1 is a front perspective view of an all in one adjustable receiver hitch, showing my new design with a cover in a lowered position;

FIG. 2 is a rear perspective view thereof, illustrated with the cover in a raised position;

FIG. 3 is a right-side elevational view of FIG. 1;

FIG. 4 is a left-side elevational view of FIG. 1;

FIG. 5 is a rear elevational view of FIG. 1;

FIG. 6 is a front elevational view of FIG. 1;

FIG. 7 is a top plan view of FIG. 1; and,

FIG. 8 is a bottom plan view of FIG. 1.

The broken lines showing a hitch ball assembly in FIGS. 1 and 2 depict environmental matter and form no part of the claimed design.
